UNITED STATES PATENT OFFICE.

JULIUS L. CABLE, OF BOSTON, MASSACHUSETTS, ASSIGNOR TO THE CABLE CORPORATION, OF BOSTON, MASSACHUSETTS, A CORPORATION OF MASSACHUSETTS.

LEG FOR FOLDING COTS.

Application filed January 20, 1925. Serial No. 3,583.

This invention relates to certain improvements in folding cots of the type disclosed in my prior Patent #1,507,906, in which the frame and legs are formed from semi-tubular metal and in which the legs are each connected to the side bars, or rails by means of a form of connector which is rigidly connected to the leg and fitted within and pivotally connected to the end portion of 10 the adjacent side bar or bars, as the case may be.

More specifically the invention relates to an improvement on the form of joint for the above purpose disclosed in my application 15 Serial No. 726,699 and has for its objects to provide a form of connection or T-head for the legs which is so constructed that it may be made of waste pieces of stock, which is adapted to be more readily assembled than is the previously employed construction, so that a saving of manufacturing expense will be secured and which will be better adapted to withstand the strains 20 to which it is likely to be subjected than said previous constructions.

I accomplish these objects in the manner hereinafter described and as illustrated in the accompanying drawings, in which:

Fig. 1 is a side elevation of a folding cot 30 of the type referred to and containing an embodiment of my invention.

Fig. 2 is a detail sectional view on an enlarged scale, at line 2—2 of Fig. 1.

Fig. 3 is a similar view, at line 3—3 of 35 Fig. 2.

Fig. 4 is a sectional view at line 4—4 of Fig. 3.

Fig. 5 is a view, similar to Fig. 3, of one 40 of the end side bar and leg connectors.

Fig. 6 is an end view thereof.

Fig. 7 is a sectional view at line 7—7 of Fig. 6.

Figs. 8 and 9 are side and perspective 45 views, respectively, of one of the middle connector members.

Figs. 10 and 11 are similar corresponding views of one of the end connector members.

In the drawing, the cot illustrated comprises side bars *a*, end bars *b* and a pair of 50 crossed, pivotally connected legs *c* at the middle and a similar pair of legs *d* at each end, all being formed of strips of metal

bent in semi-tubular form, with parallel sides and semi-cylindrical middle portions.

The specific form of connection between 55 the middle legs *c* and the side bars is illustrated in Figs. 2, 3, 4, 8 and 9 and comprises a pair of connector members *e* each of which are identical in form and each of which consists originally, of a flat metal plate or 60 blank, of approximately rectangular form, and as illustrated in Fig. 9, one of the longer edge portions of the blank being turned inward or bent cylindrically through 65 90°, forming a curved portion *e*¹, so that 65 when the two members, which form the connector, are placed together in opposite relation, and are held so that their flat portions are parallel, the bent portions *e*¹ will 70 form a practically continuous semi-cylindrical surface, corresponding to the inner 75 surface of the rounded portion of the side bar. Ears or lugs *e*² are formed at each of the opposite corners from the curved portion *e*¹, said ears being formed at approximately 45° to the edges of the blank in opposite relation and the extreme corner portion being cut off obliquely, so that an end edge *e*³ is formed on the ends of the lugs of each member which is adapted to engage 80 the opposite member when the members are placed in opposite relation, and the sides thereof are parallel. Each member *e* is a duplicate of the other, and, in order that the lugs *e*² thereof will overlap and lie side by 85 side in engagement when a pair of members are in assembled position, one lug of each member is set at a slightly greater distance from the opposite edge *e*¹ than the other, so that the right hand lug of one 90 member will overlap the left hand lug of the other member, when two members are placed in opposite relation, and one lug of each member will lie out-side and the other 95 inside the directly opposite lugs of the other member, as shown in Figs. 2, 3 and 4. As the edges of the curved portions of each pair of members meet, when assembled, in order to provide a wider meeting surface, at the edges of the curved portions, two inwardly bent portions *e*⁴ are formed in the edge portions thereof. When in assembled position, the distance between the inner surfaces of the sides of the members 100

2

e is substantially less than the width of the legs *e* measured from the middle of their semi-cylindrical portion to the plane of the edges of their sides. To permit the end portion of each leg to extend between said surfaces and to provide a means for rigidly attaching the leg to the members *e*, the edge portions of the sides of the legs, for a distance corresponding to the width of said members, are bent outwardly at right angles to form flanges *c*¹, having their faces in the same plane surface and at a distance from a parallel plane to the semi-cylindrical portion equal to the perpendicular distance between the inner surfaces of a pair of members when assembled, so that when the leg is placed between the members one member will engage the flanges and the other the middle of its semi-cylindrical portion of the leg, and the members will be in the relative position in which it is intended that they be held, i. e. with the edges of the portions *e*¹ engaged, the sides parallel, and the ends of the lugs *e*² of each member engaged with the sides of the other member. In this position also, the upper end edges of the flanges *c*¹ will be pressed firmly against the rounded portion *e*¹ of one of the members and the lower edge of this member will engage the shoulders *c*² formed on the leg by bending out the flanges *c*¹, as shown in Fig. 2.

In practice, when the parts are stamped out, or otherwise formed, rivet holes are punched therein, so that when these parts are assembled they may be readily secured in the positions in which they are intended to be held, a pair of rivets *f* being passed through the sides of the members *e* and through the flanges *c*¹, so that said members are firmly clamped together and against opposite portions of the leg. When thus assembled, each pair of members *e* unite to form a T-head for each middle leg having a semi-cylindrical upper edge and parallel sides, the exterior surfaces of which are adapted to conform to the interior surfaces of the side bars *a*, so that the end portions of the side bars may be placed in position on said T-heads and pivotally connected thereto by rivets *g*, which are passed through the sides of the bars and through the sides of the members *e*, adjacent the ends of the latter, to permit the bars to be swung thereon between positions of alignment and parallel folded positions, the corners of the members *e* adjacent the pivots *g* being slightly rounded to permit this movement. The construction of the connectors, or T-heads on the ends of the end legs *d* is similar to that for the middle legs, but differ therefrom in certain details. The members *k* and *h* from which they are constructed are formed from flat blanks similar to that shown in Fig. 10, but are made in pairs from dies which are

somewhat differently constructed. These blanks are notched at each end, and the portion above the notches is bent into partly cylindrical form, the end portions *k*¹, *h*¹ thereof being bent into nearly semi-cylindrical form, so that when a pair of members are placed together they form a cylindrically shaped projection which is adapted to be received by either of the end sockets of the end bars *b*, as described in my said prior patent. A pair of lugs *k*² and *h*² are also formed on each member below the end notches, said lugs being bent into a position at right angles to the side of the member and being disposed perpendicularly to the longitudinal edges of the member. The lugs *k*² and *h*² are, in this form, preferably so arranged that the lugs *k*² on the member *k* will be engaged with the inner sides of the lugs *h*² of the member *h*. The end portions of the legs *d* are bent outward to form flanges *d*¹, similar to flanges *c*¹, and the distance between the parallel edges of said flanges *d*¹ is such that they fit closely between the inner sides of lugs *h*², so that when the leg is placed between the members, with its end engaged with the semi-cylindrical portions thereof, the edges of the lugs *h*² will engage the sides of the flanges *d*¹. Rivets *i* are passed through the sides of the members *g*, *h* and through the flanges *d*¹, so that the members *k*, *h* are firmly clamped together and against opposite portions of the leg, the sides of the member *h* being clamped against the face sides of the flanges *d*¹ and the edges of the flanges *k*² being clamped against the opposite sides thereof, the inner side of the member *k* also being clamped against the rounded portion of the leg. The cylindrically shaped surface formed by the portions *k*¹, *h*¹ of the members corresponds to the inner surface of the end portions of side bars *a*, which are placed in position thereon and pivotally connected thereto by rivets *j*, which pass through both members *k*, *h* and the sides of the bars in the manner already described with relation to the connecting head, or connector at the middle, the side bar, in each instance, being extended along the head as far as practicable, as shown in Fig. 5.

With the above described forms of connectors between the legs and the side bars, the manufacturing operations are substantially simplified, as the connector members may be placed on opposite sides of the legs and the rivets may be inserted and secured more readily than with said prior construction. At the same time the connection secured is very rigid and will withstand any strain to which it is likely to be subjected, several abutting shoulders between the leg and the members being provided, which prevent any undue strain from being placed on the rivets.

While the above described construction is

illustrated in connection with a folding cot, the same construction may be employed to advantage in connection with folding chairs, or the like, of similar construction.

I claim—

1. A leg of channel-form metal, adapted for use in connection with a channel-form metal side bar of a folding cot, and having the edge portions of its sides at its said upper end extending transversely outward to form oppositely disposed flanges, a pair of metal plate sections having oppositely disposed head portions shaped to correspond exteriorly to opposite portions interiorly of the side bar and having ear portions arranged in parallel relation with each other and with the faces of said flanges and means engaging said ear portions and flanges to clamp the same rigidly together. 70
2. A leg of channel-form metal, adapted for use in connection with a channel-form metal side bar of a folding cot, and having the edge portions of its sides at its upper end extending transversely outward to form oppositely disposed flanges, a pair of metal plate sections having ear portions arranged in parallel relation with each other and with the faces of said flanges and rigidly secured thereto and to each other, and said sections having head portions extending upwardly and transversely from said ear portions, the upper edge portions thereof being extended towards each other, so that their edges meet, to form a T-head corresponding exteriorly to the interior of the side bar, within which it is adapted to be fitted and to which it is adapted to be pivotally connected. 80
3. A leg of channel-form metal, adapted for use in connection with a channel-form metal side bar of a folding cot, said leg having flanges formed integrally with its sides at its upper end and extending at each side thereof in a common plane and a pair of metal plate sections arranged in parallel relation with said flanges and having means extending therethru and thru said flanges to clamp the same rigidly thereby, said sections having their upper edge portions turned towards each other, to provide a top bearing face which extends longitudinally at right angles to the leg and conforms transversely to the interior of the side bar, so that it may be fitted therein and provide a support therefor. 90
4. A leg of channel-form metal, adapted for use in connection with a channel form metal side bar of a folding cot, and having the upper end portions of its sides bent outwardly to form oppositely disposed flanges arranged in the same plane, a connector therefor comprising a pair of metal plates arranged with one in engagement with said flanges and one held in parallel relation thereto, and means extending thru said plates and flanges to clamp them rigidly together, the upper edge portions of said plates being inturned and adapted to be fitted within the side bar, so that the in-turned portions will bear against the middle portion of the bar and the sides of the plate will engage the sides of the bar when the leg is held in right angular relation thereto. 100
5. A leg of channel-form metal, adapted for use in connection with a channel-form metal side bar of a folding cot, and having a pair of laterally extending flanges formed continuously with the upper portion of its sides, metal connector plates respectively arranged one against said flanges and the other against the opposite portion of the leg, and means engaging said plates and flanges to clamp said plates together and against said opposite portions of the leg and form a rigid connection therebetween, the upper edge portions of said plates being adapted to be fitted into the side bar and have a pivotal connection therewith. 110
6. A leg of channel-form metal adapted for use in connection with a channel-form metal side bar of a folding cot, said leg having a portion of each side at its upper end bent outwardly to form a pair of flanges disposed in a common plane, a pair of metal plates one engaged with said flanges and the other with the opposite rounded portion of the leg, and clamping bolts extending through the plates and said flanges at each side of the leg to secure the same thereto, the upper edge portions of said plates being bent towards each other to form a substantially continuous rounded surface corresponding to the inner surface of the rounded portion of the side bar and with which said upper portions of said plates are engaged. 120
7. A leg adapted for use in connection with a side bar of a folding cot, both leg and side bar being formed of semi-tubular metal having parallel sides and an intermediated rounded portion; said leg having a portion of each side at its upper end bent outwardly to form a pair of flanges disposed in a common plane, a pair of metal plates one engaged with said flanges and the other with the opposite rounded portion of the leg, and having means to clamp the same thereagainst, each of said plates having a lug formed integrally therewith and extended into engagement with the other at opposite sides of the leg and having their upper edge portions inwardly curved and adapted to be fitted within the side bar against the rounded portion thereof. 130
8. A leg adapted for use in connection with a side bar of a folding cot, both leg and side bar being formed of semi-tubular metal having parallel sides and an intermediate rounded portion, the sides of said leg at the upper end thereof having their edge portions bent outwardly to form flanges with the face sides thereof in the same plane surface, 140

a pair of metal plates one of which is engaged with the faces of said flanges and the other with the opposite middle portion of the leg and clamping bolts extending through said plates and flanges, the upper edge portions of said plates being inturned and adapted to be fitted within an end portion of the side bar and pivotally connected thereto and said plates each having an in-turned lug arranged to overlap in engagement with each other and hold the plates in spaced relation.

9. A leg adapted for use in connection with a side bar of a folding cot, both leg and side bar being formed of semi-tubular metal having parallel sides and a semi-cylindrically shaped middle portion, the sides of said leg at the upper end thereof having their edge

portions bent outwardly to form flanges with the face sides thereof in the same plane surface, a pair of metal plates one of which is engaged with the faces of said flanges and the other with the opposite middle portions of the leg and clamping bolts extending through said plates and flanges, the upper edge portions of said plates being inturned and adapted to be fitted within an end portion of the side bar and pivotally connected thereto and said plates each having a pair of in-turned lugs arranged at opposite sides of the leg in position to overlap each other in close engagement and to engage the side of the opposite plate at their ends.

In testimony whereof, I have signed my name to this specification.

JULIUS L. CABLE.
